UNITED STATES PATENT OFFICE.

WILLIAM P. RICE, OF SHELBIANA, KENTUCKY.

MINER'S LAMP.

1,024,362.

Specification of Letters Patent. Patented Apr. 23, 1912.

Application filed January 14, 1911. Serial No. 602,627.

To all whom it may concern:

Be it known that I, WILLIAM P. RICE, a citizen of the United States, residing at Shelbiana, in the county of Pike and State 5 of Kentucky, have invented new and useful Improvements in Miners' Lamps, of which the following is a specification.

The invention relates to lamps, and more particularly to the class of miners' lamps.

10 The primary object of the invention is the provision of a lamp in which an air passage is disposed within the wick tube, the passage being extended into the body of the lamp, so that air heated by the flame will enter 15 the interior of the lamp for the melting of the contents thereof, and also effect an increased illuminating power.

Another object of the invention is the provision of a lamp of this character in which 20 air may be admitted to the interior thereof, so as to increase the fluidity of the fuel confined therein, thus assuring perfect combustion of the fuel and increasing the light therefrom.

25 A further object of the invention is the provision of a lamp which is simple in construction, thoroughly reliable and efficient in operation, and inexpensive in manufacture.

With these and other objects in view, the 30 invention consists in the construction, combination and arrangement of parts, as will be hereinafter more fully described, illustrated in the accompanying drawings, and pointed out in the claim hereunto appended.

35 In the drawings: Figure 1 is a side elevation of a lamp constructed in accordance with the invention. Fig. 2 is a vertical longitudinal sectional view thereof. Fig. 3 is a top plan view.

40 Similar reference characters indicate corresponding parts throughout the several views of the drawings.

Referring to the drawings by numerals, the lamp comprises a conical-shaped body 5, 45 preferably constructed from tin, although it may be made from any other suitable material, and is provided with a wick tube 6, the latter being rearwardly inclined and communicating with the interior of the body, 50 and in which is disposed the ordinary wick 7 which absorbs the oil contained within the body 5 of the lamp for lighting purposes when ignited. The body 5 of the lamp at

its top may be closed in any suitable manner, preferably by a removable cap 8 which permits the filling of the body 5 with oil when required. Suitably secured to the body 5 exteriorly thereof is a hanger hook which is of the ordinary well-known construction, whereby the lamp may be mounted upon a 60 miner's cap in the usual manner. Formed on the wick tube 6 is an air tube 10, the same being extended within the body 5 of the lamp and terminates in a circular end 11, the latter being soldered or otherwise secured within the said body contiguous the bottom thereof, the circular end 11 being suitably perforated so that air admitted through the air tube 10 will be let into the said body 5. The air tube 10 is longitudinally disposed on the wick tube 6 and co-extensive therewith, the air tube 10 being secured to the wick tube 6 in any suitable manner. Telescoping within the outer end of the air tube 10 is a wire 12, the same being 70 provided with an outturned free end 13 which is adapted to be thrown into the path of the flame issuing from the wick 7 or away from the same. Thus, it will be seen that when the outturned end 13 of the wire 75 is turned into the path of the flame issuing from the wick 7, the air admitted into the tube 10 will be heated, and when the said outturned end 13 is shifted out of the path of the flame from the wick, the air admitted 80 into the body 5 of the lamp will be cool. 85

What is claimed is:

In a miner's lamp, a frusto-conical-shaped body having a wick tube projecting outwardly and upwardly therefrom, a wick disposed within the tube, an air tube coextensive with the wick tube and contiguous thereto, the inner end of the said air tube being extended interiorly of the body and terminating in a circular perforated end 95 resting upon the bottom of the said body, and a wire rotatably mounted in the outer end of the air tube and having an outturned end adapted to be swung into and out of the path of the flame of the wick when ignited. 100

In testimony whereof I affix my signature in presence of two witnesses.

WILLIAM P. RICE.
